United States Patent Office

Des. 213,753
Patented Apr. 1, 1969

213,753

BICYCLE

Viktor Schreckengost, Cleveland, Ohio, assignor to The Murray Ohio Manufacturing Co., Nashville, Tenn., a corporation of Ohio

Filed June 13, 1968, Ser. No. 12,328

Term of patent 14 years

Int. Cl. D12—11

U.S. Cl. D90—20

FIGURE 1 is a side elevational view of a bicycle showing my new design;

FIGURE 2 is a top plan view thereof:

FIGURE 2 is a top plan view thereof,
FIGURE 3 is a bottom plan view thereof:

FIGURE 3 is a bottom plan view thereof;
FIGURE 4 is a front elevational view thereof;

FIGURE 4 is a front elevational view thereof; FIGURE 5 is a rear elevational view thereof;

FIGURE 3 is a rear elevational view thereof; The dominant features of my design reside in the portions shown in full lines. The wheel and tire is fragmentarily shown in FIGURE 1 for convenience of illustration only.

The elements shown in broken lines are omitted from FIGURES 2 through 5 for convenience of illustration.

I claim:

The ornamental design for a bicycle, substantially as shown and described.
